UNITED STATES PATENT OFFICE.

WILLET C. WELLS AND FRANK E. WELLS, OF COLUMBUS, OHIO.

APPARATUS FOR EXPRESSING WAX FROM PETROLEUM-DISTILLATES.

1,344,745.

Specification of Letters Patent. Patented June 29, 1920.

Original application filed April 23, 1914, Serial No. 833,897. Divided and this application filed April 12, 1919. Serial No. 289,531.

To all whom it may concern:

Be it known that we, WILLET C. WELLS and FRANK E. WELLS, citizens of the United States, residing at Columbus, in the county 5 of Franklin and State of Ohio, have invented certain new and useful Improvements in Apparatus for Expressing Wax from Petroleum-Distillates, of which the following is a specification.

10 This application for patent is a division of application Serial Number 833,897 filed by us on April 23, 1914, for process of expressing wax from petroleum distillates, the division being made for the purpose of 15 covering the apparatus in this application and permitting the original application to be prosecuted separately for the process therein described and claimed, the apparatus being clearly disclosed and described 20 in the said original application.

The invention relates to apparatus for expressing wax from heavy viscous distillates of petroleum, shale oils, and the like.

The apparatus universally employed for 25 accomplishing this purpose includes filtering pads spaced apart by rings thereby forming compartments for the collection of the wax or congealed substance between the pads, the liquid passing off through the 30 pads. These pads are composed of a metal plate having a central opening and on each side of this plate are arranged plates having a registering central opening and perforations distributed over the plate, these 35 perforations having a protruding edge or lip which prevents the outer plate from lying flat against the inner one. Over these perforated plates is placed a strong and thick closely woven cotton cloth having a 40 registering central opening and completely covering the face of the perforated plate. The filter pad thus constructed is set on edge in the frame of a press, a spacing ring is placed on edge in contact therewith, then 45 another pad is placed and another ring, and so on. When the press has been built up in this manner to the capacity desired fastening means are applied and the position of all the parts is fixed.

50 The distillate to be treated is chilled in its course from a pressure pump to the press and is admitted into the press from one compartment to another through the central openings mentioned, and fills the compartments; the pressure exercised on the

distillate forces the liquid portion thereof through the cloth strainer through the perforations and it drains off downwardly between the plates. The wax of course remains in the compartments. Theoretically 60 the entire face of each pad is available as a strainer surface, and if the practice followed the theory there would be no need of improvement. But, on the contrary, the effectiveness is much diminished by the flattening of the lip like edges of the perforations against the central plate under the pressure needed to make the press firm, and the imperforate area is thereby greatly increased so that the portion of the face of 65 the plates useless for the passage of the distillates is very large compared with the portion which can be so utilized. Further the fiber of cotton is as straight and smooth as wire and the thread in the cotton cloth 70 is practically impervious, and therefore the liquid straining through cotton cloth passes between the threads. If the cloth is closely woven, as would be the case in this art, great pressure is required to force the distillate through it and consequently great 75 strength of material is needed to sustain the pressure over the span of the perforations. Since in this use the cloth must be strong and no material alteration can be made in 80 the apparatus at present used for this purpose, special treatment must be given to the distillates to enable them to be passed through the press without injury to the press. Accordingly the universal practice 85 is to reduce the viscosity of the distillates by decomposition to about 60 viscosity to press them, and this denotes a loss of three-fourths of the natural value of the undecomposed distillates of the same petroleum. 90

Applicants have devised a press which will obviate this loss and the difficulties attendant upon the use of the kind of press described above. They build a heavy woven wire central frame work for the filtering 100 pad and over the same on each side place successive layers of increasingly finer woven wire, the outer layer giving ample support to the straining cloth without materially obstructing the passage of liquid there-through. Through this wire structure there is a central opening similar to that in the solid pad above described. Over this wire frame is placed a closely woven woolen cloth in the same manner as the cotton cloth is 110

disposed on the pad above described, and the filtering pads and spacing rings are arranged in the same manner also, and the distillates are fed into the press for treatment in the same manner. The results however are vastly different and in favor of our apparatus for the following reasons:—

Each hair of wool is knobby, not smooth like the fiber of cotton, and however closely it may be woven or however hard it may be twisted it remains pervious to liquids and forms the best conceivable strainer to separate the amorphous or vaseline congealing portion of the distillates. The fine wire covering of the frame of the pad gives ample support to the woolen cloth without materially obstructing the passage of liquid therethrough, and the wire structure for the frame of the pad gives unobstructed drainage for the liquid which passes through the cloth strainer.

The method of converting petroleums and shale oils into commercial products without impairment of their constitutions as described, for instance, in our Patent No. 877620 issued January 28, 1908, produces wax distillates of more than ten times the viscosity possible to be pressed by the above described presses in common use; to prepare these viscous wax distillates for the market with the presses in common use requires decomposition by heat whereby the distillates lose more than three fourths of their intrinsic value, and their broken substances must then be evaporated off sufficiently to form a residue having the degree of viscosity to meet requirements.

The apparatus we use may now be briefly described. In the drawings hereto attached and hereby made a part of this specification, Figure 1 shows our press in side elevation; Fig. 2 shows the filter mat with parts broken away to disclose the layered construction; Fig. 3 shows the ring spacer; Fig. 4 shows a section of the mat and contiguous ring spacers on a greatly enlarged scale for the purpose of illustration; and Fig. 5 shows an end view of the apparatus partly broken away.

Referring to the drawings the press frame supports are shown at 1 and 1^a, the support 1 carrying the platen 8 which may preferably be integral with the frame. Frame rods 2 and 3 are mounted at one end in platen 8 and at the other end in the frame support 1^a. Tie rods 4, 5, 6 and 7, in such number as may be desired, are secured at one end in the platen 8 and are inserted at their other ends through the platen 9 which is movably mounted on the frame rods 2 and 3. The filter pad 10 is composed of the layers of wire of different fineness of mesh shown at 11, 12 and 13, and additional layers of progressively increasing fineness may be used if desired; both faces

of this built up pad are covered with a closely woven woolen cloth appearing at 14 and 15. A central opening 16 pierces the filter pad 10 for the admission of the distillates and also for compressed air for 70 drying the residue if desired.

These pads are set on edge vertically for use and between each two is arranged a spacing ring 17 to separate the pads thereby providing a compartment into which the 75 distillate is fed under pressure for filtration and in which the wax residue is deposited. The ring 17 is provided with the diametrically disposed rods 17^a and 17^b which give rigid lateral support to the body 80 of the filter pad and prevent any warping or sagging of the pad under the pressure of the distillate or the air used in the process. Hangers 18 and 19 take over the frame rods 2 and 3 to position the spacing ring 85 thereon and similar hangers are shown at 20 and 21 for the pads.

When the desired number of pads and ring spacers have been placed in the frame the end platen 9 is forced into moving contact with them by the hydraulic cylinder 22 and when they are firmly positioned the nuts are run up on the tie rods 4, 5 and so on to fix the platen. The press is now ready for use and the distillate is introduced 90 through the opening 24 in the platen 9 into the central longitudinal registering openings designated at 16, whence it passes into the ring spaces and under the pressure is filtered through the woolen covering of the 100 pads and through the wire layers and the resulting liquid drains down through the wire structure and drips out at the bottom of the press into the pan or receiver 25. The pressure applied to the distillate may 105 be regulated as desired to produce the proper degree of dryness in the wax thus expressed. Ordinarily the introduction of distillate is stopped before the run is completed and a uniform degree of dryness is 110 given to the charge by the use of compressed air introduced in the same manner as the distillate. The press is then knocked down, the wax removed and the press may then be set up for another run, and this may be re- 115 peated, obviously, as often as required.

The increased beneficial results of the use of our press over the presses in common use both in respect to its effectiveness in dealing with distillates and also in respect to the 120 character of distillate which it successfully operates upon, have been above set forth, and we desire to have the benefit of any variations in the construction of the apparatus which fall within the scope of the ap- 125 pended claims.

We claim:—

1. A filtering pad comprising a frame of coarse woven wire, a covering of finer woven wire imposed thereon, and a woolen fabric 130

strainer disposed upon the face of said covering, which structure uniformly and adequately supports said strainer and affords unrestricted drainage therefor.

- 5 2. A filtering pad for a filter press comprising a frame of coarse woven wire, a covering of finer woven wire imposed thereon, a woolen fabric strainer disposed upon the face of said covering, which structure uniformly and adequately supports said strainer and affords unrestricted drainage therefor, said pad having a transverse opening therethrough, and suspending means for said pad carried on said frame.

3. A filter press composed of a series of 15 filtering pads fabricated substantially as described, and spacing members interposed between said pads adapted to maintain a uniform space between the faces of said pads.

In testimony whereof we have hereunto signed our names in the presence of two witnesses.
